BY Arthur C. Brem

ATTORNEY

UNITED STATES PATENT OFFICE

137,061

DESIGN FOR AN ICE CRACKING BAG

Wilber Lawrence Mellor, Johnson County, Kans.

Application August 27, 1943, Serial No. 111,005

Term of patent 3½ years

To all whom it may concern:

Be it known that I, Wilber Lawrence Mellor, a citizen of the United States, residing in Johnson County, State of Kansas, have invented a new, original, and ornamental Design for Ice Cracking Bags, of which the following is a specification, reference being had to the accompanying drawing, forming part thereof.

Fig. 1 is a perspective view of an ice cracking bag showing my new design.

Fig. 2 is a side elevational view thereof.

I claim:

The ornamental design for an ice cracking bag, as shown.

WILBER LAWRENCE MELLOR.
